INFLATABLE BALL

Howard M. Pierce, Brooklyn, N. Y., assignor to
 A. G. Spalding & Bros., New York, N. Y., a corporation of New Jersey

Application March 12, 1932. Serial No. 598,322

2 Claims. (Cl. 273—65)

The present invention relates to inflatable balls and embodies, more specifically, an improved ball having an inflatable bladder, means being provided to effectively secure the bladder to the cover 5 of the ball and enable the same to be removed and replaced with facility.

A great number of inflatable ball constructions have been provided with a view to facilitating the removal and replacement of bladders from within 10 the ball covers, as well as to enable the bladder to be effectively positioned therein, these previous constructions embodying flaps and other engaging elements which are adapted to be removably secured in position to hold the bladder effectively 15 within the cover of the ball. These devices, while effectively securing the bladder within the cover, have been rather difficult to manipulate and in addition to being heavy and cumbersome have been rather complex and expensive to manufacture. Furthermore, the bladders which have been used in connection with such securing devices have had valves secured therein of the type commercially used for inflating vehicle tires. These valves, being formed of metal and having spring pressed 25 check valves, have been difficult to secure in the bladder in an air-tight fashion and therefore have proved unserviceable in use. Previous valves which have not been of the metallic type have proven quite inadequate to preserve an air-tight 30 connection against the internal pressure of the inflating fluid and have invariably leaked.

An object of the present invention, accordingly, is to provide an inflated ball having an improved form of valve to facilitate the inflation thereof, 35 the ball having a bladder which is adapted to be effectively inflated without the use of a metallic valve.

A further object of the invention is to provide a ball of the above character having an inflating 40 neck and means attached thereto to prevent the inflating fluid from escaping from the bladder after the bladder has been inflated.

A further object of the invention is to provide an improved non-metallic valve construction for 45 the bladders of inflatable balls, the valve construction being simple and effective in preserving the inflating connection in an air-tight condition.

A further object of the invention is to provide 50 an inflatable ball having a bladder and an improved means for connecting the bladder to the cover of the ball.

A further object of the invention is to provide 55 an inflatable ball having a cover and a bladder, the cover and bladder being provided with cooper-

ating means to facilitate the removal and replacement of bladders within the ball cover.

Further objects, not specifically enumerated above, will be apparent as the invention is described in greater detail in connection with the 60 accompanying drawing wherein:

Figure 1 is a plan view of a ball having a bladder secured to the ball cover and provided with an inflating connection or valve, and means for connecting the bladder to the cover in accordance 65 with the present invention.

Figure 2 is a view in section, taken on line 2—2 of Figure 1, and looking in the direction of the arrows.

Figure 3 is a view in section, taken on line 3—3 70 of Figure 2, and looking in the direction of the arrows, Figure 3 showing the manner in which the bladder is inflated after being secured within the ball cover.

Referring to the drawing, an inflatable ball 75 cover is shown at 10 as being provided with an aperture 11 through which an inflating stem 12 is adapted to pass. The stem 12 may be of such length as to lie flush with the cover of the ball or may be countersunk with respect thereto if desired. Under the cover and concentric with the aperture 11, a rubber disc 13 is provided, this disc being suitably secured to the cover and having a leather disc 14 attached thereto. Under the leather disc 14 is a latex or crude rubber disc 15 which 80 provides a desired cushioning effect upon the elements. Stitches 16 may be provided to secure the discs in position, each disc being formed with an aperture which is aligned with the aperture 11, whereby the inflating neck 12 of a bladder 12' may 85 be passed therethrough to receive an inflating tool, as will be described hereinafter.

Under the leather washer or disc 14, the heads 17 of internally threaded rivets or shafts 18 are secured, the recessed threaded shafts 18 extending 90 from the latex washer 15, as clearly shown in Figure 2.

About the inflating neck 12, a rubber washer 19 is secured, the washer 19 being formed with a restricted aperture 20 to receive the inflating neck 100 12 and compress the same tightly as shown in Figure 2. The compression of the neck 12 by washer 19 is sufficient to prevent the escape of fluid from the bladder 12' and washer 19 is provided with a plurality of apertures 21 to receive 105 the threaded shafts 18. Screws 22 extend within the threaded shafts 18 and are provided with heads 23 which engage under the washer 19 and secure the same effectively in the position shown 110 in Figures 2 and 3.

After the bladder, with its washer 19, has been secured in the position shown, the ball may be inflated by inserting a round nosed hollow needle 24 through the hollow neck 12, as shown in Figure 3 and fluid introduced through a fitting 25 to which the needle 24 is secured. When the fitting and needle are removed, the washer 19 constricts the neck 12 and the escape of the fluid therefrom is thus prevented.

10 From the foregoing, it will be seen that the means for securing the bladder to the cover is simple and effective in operation. The cooperating parts for effecting the securing of the bladder to the cover are of such character that they may be readily constructed and effectively operated to replace bladders conveniently. Furthermore, the inflating valve is simple in construction and effective to prevent the escape of the inflating fluid from the bladder, the valve having no metallic parts whatever.

15 While the invention has been described with specific reference to the accompanying drawing,

it is not to be limited, save as defined in the appended claims.

I claim as my invention:

1. An inflatable ball having a cover formed with an aperture, a bladder having an inflating neck, a washer secured within the cover and about the aperture, threaded shafts secured under the washer, a rubber washer formed with an aperture in which the neck is adapted to be constricted, and means to secure the last named washer to the threaded shafts. 20

2. An inflatable ball having a cover formed with an aperture, a bladder having an inflating neck, a washer secured within the cover and about the aperture, threaded shafts secured under the washer, a rubber washer formed with an aperture in which the neck is adapted to be constricted, and threaded members to engage the threaded shafts and secure the last named washer to the cover of the ball. 25
